UNITED STATES PATENT OFFICE.

JULIUS C. HINZ, OF DETROIT, MICHIGAN.

OIL-BURNER.

No. 920,572.

Specification of Letters Patent.

Patented May 4, 1909.

Application filed May 27, 1908. Serial No. 435,203.

To all whom it may concern:

Be it known that I, JULIUS C. HINZ, a citizen of the United States of America, residing at Detroit, in the county of Wayne and State 5 of Michigan, have invented certain new and useful Improvements in Oil-Burners, of which the following is a specification, reference being had therein to the accompanying drawings.

10 This invention relates to liquid fuel burners and especially to oil burners of the wickless type.

The invention consists in the matters hereinafter set forth, and more particularly 15 pointed out in the appended claims.

In the drawings, Figure 1 is a plan view of a burner embodying features of the invention. Fig. 2 is a view in section on or about line $x-x$ of Fig. 1.

20 Referring to the drawings, 1 indicates a hollow metallic casing of any preferred symmetrical form, and having a central aperture 2 of considerable size in its top 3. A substantially horizontal fuel supply pipe 4 leading from any convenient source of supply 25 passes through the side wall 5 of the casing and has a suitable supporting fitting 6 thereon, its inner end being branched and acting as support for a burner cup 7. The latter 30 is centrally disposed in the aperture 2 with its upper rim flush with the casing top 3 and is proportioned so that there is sufficient space around it for air from the casing to pass therethrough. The cup is divided into a 35 plurality of substantially circular compartments each provided with a central or axial upright nipple 8 extending from the top of the compartment through its base and screw-threaded into or otherwise properly secured 40 to one of the branches of the fuel pipe 4. The space between each nipple and the wall of its compartment is packed either with a mixture of shredded asbestos and fire clay 9 or like suitable refractory material which 45 will readily absorb liquid. A crown 10 with radial ducts or passages 11 in its upper face is secured in the upper end of each nipple so that oil passing up through the nipple flows over onto the surrounding mass 9 which becomes soaked thereby. The compartments 50 are connected with each other by grooves 12 in the upper edge of the division walls.

A plurality of symmetrically disposed slides 13 of any preferred form are secured in 55 the wall 5 of the casing; a central aperture of considerable size is formed in the casing base

14 which is controlled by a damper 15 of suitable construction; preferably this is a circular disk having an axial spindle 16 screw-threaded through the central boss 17 60 in a spider 18 of appropriate design secured across the base aperture.

The operation of the burner which is especially adapted for pottery kilns, brick furnaces, and the like, is as follows:—The 65 fuel oil is poured through the supply pipe so that it overflows through the ducts of the nipple crown into the surrounding mass of clay until the latter becomes thoroughly impregnated. The oil is then ignited and a 7 sufficient amount allowed to flow through the fuel pipe thereafter to keep the flame at constant height. Air is admitted through the central damper and the flame is directed obliquely upward from the burner by proper 75 manipulation of the slide in the side of the casing as the opening of a slide at one side of the case deflects the flame obliquely in the opposite direction. By this arrangement a smokeless flame is obtained and as the metal 80 of the burner is shielded by the clay and asbestos, save at the rim, the flame does not carry away any salts or oxids from the metal to be deposited on and disfigure articles in the kiln in which the burner may be used. 85 The burner is practically indestructible and simple and readily constructed.

Obviously changes in the details of construction may be made without departing from the spirit of the invention, and I do not 90 care to limit myself to any particular form or arrangement of parts.

What I claim as my invention is:—

1. A liquid fuel burner comprising a casing having an air outlet in its top air inlets in the 95 casing sides and base, a cup in the outlet having a plurality of compartments therein, a bed of refractory absorbent material filling each compartment, a central upright supply nipple extending from the base of each compartment to the surface of the bed, a crown on each nipple having radial distributing 100 passages in its upper end adapted to direct liquid from the nipple evenly over the surface of the bed, a fuel supply pipe connected 105 to the nipples, an adjustably secured damper governing the air inlet in the casing base, and a plurality of adjustable slide closures governing the air inlets in the casing side.

2. A liquid fuel burner comprising a casing 110 having an air outlet in its top, an air inlet in its base, and air openings in its sides, a fuel

supply pipe through the casing side, a cup supported on the pipe centrally in the outlet and provided with a plurality of compartments connected by channels in the upper 5 edges of the division walls, a bed of refractory absorbent material filling each compartment, an upright axial nipple in each compartment connected with the fuel pipe, a crown on the upper end of each nipple substantially flush 10 with the surface of the bed having passages

in its upper face adapted to distribute liquid evenly over the bed, a damper governing in the base inlet opening, and slide closures governing the side openings of the casing.

In testimony whereof I affix my signature 15 in presence of two witnesses.

JULIUS C. HINZ.
